UNITED STATES PATENT OFFICE.

WILLIAM GEORGE BEATTY, OF FERGUS, ONTARIO, CANADA.

CATTLE-STANCHION.

1,225,003.

Specification of Letters Patent.

Patented May 8, 1917.

Application filed December 20, 1915. Serial No. 67,928.

To all whom it may concern:

Be it known that I, WILLIAM GEORGE BEATTY, of the town of Fergus, in the county of Wellington and Province of Ontario, Dominion of Canada, have invented certain new and useful Improvements in Cattle-Stanchions; and I hereby declare that the following is a full, clear, and exact description of the same.

This invention relates to a cattle stanchion in which the hinged side is laterally adjustable with relation to the other three sides of the stanchion frame, the object of the invention being to so construct and arrange the component parts of the stanchion that the vertical sides can be quickly adjusted to vary the distance between them, this object being attained by providing each of the horizontal sides of the stanchion frame with a movable bracket, pivoting the lower end of the hinged stanchion side to the lower bracket, and providing the upper bracket with a latch engaging with the keeper at the upper end of the hinged side, the horizontal sides and brackets being movable through guide brackets respectively suspended from the head rail of the stall and supported from the stall floor, the movable brackets and horizontal stanchion sides being provided with toothed racks meshing with pinions journaled in the guide brackets, as hereinafter set forth and particularly pointed out in the claims.

In the drawings:

Figure 1, is a sectional elevation showing the general construction and arrangement of the component parts of the stanchion with the hinged side in its closed position, as shown in that figure.

Fig. 2, is a cross-sectional view on either of the lines 2^a—2^a, or 2^b—2^b, Fig. 1; and,

Fig. 3, is an end elevation of one of the pinions to show the locking face.

Like characters of reference refer to like parts throughout the specification and drawings.

The stanchion frame consists of an upright side *a*, two horizontal sides *a'*, *a''* extending one from the upper end of the vertical side *a* and the other from the lower end thereof, and a hinged vertical side *a³* in parallel relation to the vertical side *a* when in its closed position.

On the lower horizontal side *a''* is a bracket *b* slidable lengthwise of that side and having a bifurcated lug *b'*, in which is

pivoted the lower end *a⁴* of the hinged vertical side *a³*, a pin *b''* passing through the lugs and end *a⁴* to hinge the stanchion side *a³* to the bracket *b*.

The bracket *b* rests on the top of the lower horizontal side *a''*, and between the bottom *b⁴* of the bracket and the lower surface of the horizontal side *a''* is sufficient clearance for the toothed rack *c* which as shown in Fig. 1, meshes with the pinion *d* journaled in the sides of the guide bracket *e* embracing the stanchion side *a''* and the bottom *b⁴* of the bracket *b*, to prevent the lateral and vertical displacement of these parts while permitting them to move lengthwise of the side *a''*.

The side *a''* is provided with a toothed rack *f* corresponding to the rack *c* and also meshing with the pinion *d*, so that the rotation of the pinion will cause the simultaneous movement of the side *a''* and the bracket *b* in opposite directions, to respectively draw the vertical stanchion sides *a*, *a³* together or spread them apart for the purpose of varying the width of the space between these sides.

The guide bracket *e*, as shown in Fig. 1, is formed with a shank *g* which may be swiveled in the floor of the stall or in a swivel member (not shown) secured thereto.

At the upper end of the stanchion side *a³* is a latch guard *h* having a keeper *i* with which engages the head of the latch *j* when the stanchion side *a³* is in its closed position, the latch *j* being pivoted to a bracket *k* slidable lengthwise of the stanchion side *a'*.

On the stanchion side *a'* is a rack *l* meshing with a pinion *m* journaled in a guide bracket *o* embracing the stanchion side *a'* and movable bracket *k*, and connected with a swivel *p* suspended from the head rail *q*. The top of the bracket *k* above the pinion *m* is provided with a rack *r* meshing with the pinion.

On the racks *c* and *r* are stops *s* and *t* respectively, which engage the guide brackets *e* and *o* during the outward movement of the sliding brackets, to prevent the racks *c* and *r* passing beyond the teeth of the pinions *d* and *m*, during their outward movement, the inward movement of the slide brackets *b* and *k* being arrested by their engagement with the guide brackets *e* and *o*.

One side face of each of the pinions *d* and *m* is provided with radial grooves *u*, in which engage corresponding tongues *v* in the adjacent faces of the guide brackets to

prevent the rotation of the pinions when the wing nut w is tightened upon the axle bolt x to compress the sides of the guide brackets against the pinion, the purpose of preventing the rotation of the pinions being to lock the slide brackets in their adjusted position and maintain the hinged stanchion side a^3 in its fixed relation to the stanchion side a .

Having thus fully described the nature of my invention, what I claim as new and desire to secure by Letters Patent, is:—

1. A cattle stanchion comprising an upright side, two horizontal sides extending one from the upper and the other from the lower, end of the upright side, a bracket 15 slideable on the lower horizontal side, an upright stanchion side hinged at its lower end to the bracket, a bracket slideable on the upper horizontal side, releasable locking 20 means for securing the upper end of the hinged stanchion side to the upper bracket, racks for the upper and lower horizontal sides and for the brackets, and pinions engaging said racks to cause the sliding movements of the brackets on said horizontal 25 sides, the side faces of the pinions being provided with radial grooves and the adjacent faces of the guide brackets being provided with corresponding tongues engaging 30 in said grooves, to prevent the rotation of the pinions, and appropriate clamping means to compress the sides of the guide brackets against the pinions, whereby said tongues will engage in said grooves and prevent the rotation of the pinions to lock the slide brackets in their adjusted position and maintain the upright stanchion sides in their fixed relation.

2. A cattle stanchion comprising an upright side and two horizontal sides extending one from the upper end and the other from the lower end thereof, a bracket slideable on the lower horizontal side, an upright stanchion side hinged at its lower 45 end to the bracket and having at its upper end a keeper for the latch, and a bracket slideable on the upper horizontal side having a latch engageable with the keeper, racks for the upper and lower horizontal sides 50 and for the brackets, and pinions engaging said racks to cause the sliding movements of the brackets on said horizontal sides, the side faces of the pinions being provided with radial grooves and the adjacent faces 55 of the guide brackets being provided with corresponding tongues engaging in said grooves, to prevent the rotation of the pinions, and appropriate clamping means to compress the sides of the guide brackets 60 against the pinions, whereby said tongues will engage in said grooves and prevent the rotation of the pinions to lock the slide brackets in their adjusted position and maintain the upright stanchion sides 65 in their fixed relation.

3. A cattle stanchion comprising an upright side, two horizontal sides extending one from the upper and the other from the lower, end of the upright side, a bracket slideable on the lower horizontal side, an upright stanchion side hinged at its lower end to the bracket, a bracket slideable on the upper horizontal side, releasable locking means for securing the upper end of the hinged stanchion side to the upper bracket, 75 racks for the upper and lower horizontal sides and for the brackets, and pinions engaging said racks to cause the sliding movements of the brackets on said horizontal sides, guide brackets embracing the upper and lower horizontal sides and the sliding brackets, and pinions journaled in the guide brackets engaging with said racks, the side faces of the pinions being provided with radial grooves and the adjacent faces of the 80 guide brackets being provided with corresponding tongues engaging in said grooves, to prevent the rotation of the pinions, and appropriate clamping means to compress the sides of the guide brackets against the pinions, whereby said tongues will engage in said grooves and prevent the rotation of the pinions to lock the slide brackets in their adjusted position and maintain the upright stanchion sides in their fixed relation.

4. A cattle stanchion comprising an upright side and two horizontal sides extending one from the upper end and the other from the lower end thereof, a bracket slideable on the lower horizontal side, an upright stanchion side hinged at its lower end to the bracket and having at its upper end a keeper for the latch, and a bracket slideable on the upper horizontal side having a latch engageable with the keeper, racks for the upper and lower horizontal sides and for the brackets, pinions engaging said racks to cause the sliding movements of the brackets on said horizontal sides, guide brackets through which said upper and lower horizontal sides are movable, and pinions journaled in the guide brackets engaging with said racks, the side faces of the pinions being provided with radial grooves and the adjacent faces of the guide brackets being provided with corresponding tongues engaging in said grooves, to prevent the rotation of the pinions, and appropriate clamping means to compress the sides of the guide brackets against the pinions, whereby said tongues will engage in said grooves and prevent the rotation of the pinions to lock the slide brackets in their adjusted position and maintain the upright stanchion sides in their fixed relation.

5. A cattle stanchion comprising an upright side, two horizontal sides extending one from the upper, and the other from the lower, end of the upright side, a bracket

slidably mounted on the lower horizontal side, an upright stanchion side hinged at its lower end to the bracket, a bracket slideable on the upper horizontal side, releasable locking means for securing the upper end of the hinged stanchion side to the upper bracket, guide brackets through which the upper and lower horizontal sides and slideable brackets are movable, racks for the upper and lower horizontal sides and for the slideable brackets, and pinions journaled in the guide brackets engaging said racks to cause the sliding movements of the slideable brackets on said horizontal sides, the side faces of the pinions being provided with radial grooves and the adjacent faces of the guide brackets being provided with corresponding tongues engaging in said grooves, to prevent the rotation of the pinions, and appropriate clamping means to 20 compress the sides of the guide brackets against the pinions, whereby said tongues will engage in said grooves and prevent the rotation of the pinions to lock the slide brackets in their adjusted position and 25 maintain the upright stanchion sides in their fixed relation.

Toronto, December 17th, 1915.
